UNITED STATES PATENT OFFICE.

EARLE A. EMERY, OF DETROIT, MICHIGAN, ASSIGNOR TO DETROIT CORD MANUFACTURING COMPANY, OF DETROIT, MICHIGAN, A CORPORATION OF MICHIGAN.

FINISHING WELT.

Application filed July 9, 1925. Serial No. 42,374.

My invention relates to an improved finishing welt, an important use of which is in connection with the trimming material of automobile bodies, the welt being fastened 5 over the edge of the covering or trimming material to conceal the fastening devices employed to secure such materials in position.

The object is to provide a simple, slightly welt structure employing in its make-up a 10 minimum quantity of material and involving a minimum cost, which welt may be easily and quickly secured in place and which completely conceals the means employed to fasten the same down.

15 An advantageous feature is the provision of such a welt structure having a pair of longitudinally extending, intermediately positioned, beaded folds adapted to close together over the fastening devices and be held under tension thereby in such covering relationship, which structure is formed of a single strip of flexible material. The material of which the welt is formed has as a 20 general rule a finished side and an unfinished side and it is so folded and arranged as to present to view only the finished side. Furthermore, the welt structure is of such a character as to be capable of two distinctly 25 different methods of application.

30 In the drawings,— Figure 1 is a plan of my improved welt as applied.

Fig. 2 is a cross-sectional view taken on line 2—2, Fig. 1.

35 Fig. 3 is a cross-sectional view through a modified form of my improved welt with the lips spread apart.

Fig. 4 is a perspective of the welt in the same condition as shown in Fig. 3.

40 Fig. 5 is a cross-sectional view through my improved welt under normal conditions.

45 My improved welt in either one of the forms illustrated is made from a single strip of flexible material such as fabric, imitation leather or other suitable material which as a general rule has a finished side and an unfinished side. The strip is so folded and arranged that either in the normal position before it is applied or after it has been applied to the article the finished side only is exposed to view.

50 I take a suitable strip of the desired material, which preferably has a finished side and an unfinished side, and fold each longitudinal marginal portion toward the unfin-

ished side and over a filler cord 10, stitching the same alongside the cord at 14 to the body of the strip, forming beaded folds 16. These marginal portions extend beyond the stitching to meet between the folds 16, as 60 shown in Fig. 5, thereby covering the unfinished side of that portion of the strip intervening the folds.

The edge 12 of each marginal portion is folded over upon its unfinished side as at 18 65 and fastened down in such position. In Figs. 2 and 5 it is folded over a sufficient distance to be fastened down by the stitching 14, while in Figs. 3 and 4 it is folded over a less distance and fastened down. In 70 Fig. 4 this edge 12 is stitched down while in Fig. 3 it is shown as glued or pasted down.

The welt as illustrated in Fig. 5 exhibits to view only the finished side of the fabric. It might be used in the manner shown in 75 Fig. 5 by lifting up the marginal portions and inserting the fastening devices through the body portion which intervenes the folds 16 and then allowing the marginal portions to assume the position shown in Fig. 5, in 80 which they would hide the fastening devices. I prefer, however, to employ the welt as shown in Figs. 1 and 2.

In applying the welt as shown in Figs. 1 85 and 2 the marginal portions are spread apart, uncovering that portion of the strip intervening the folds 16, which intervening portion is indicated as 20, and in Figs. 3 and 4 the welt is shown with these marginal portions partly unfolded. The welt is applied to the article in connection with which it is to be employed by placing the unfinished side against the article, the marginal portions having been spread outwardly, so 90 that the welt assumes the position shown in Figs. 1 and 2. As the marginal portions are spread outwardly to the position shown in Fig. 2, the beaded folds 16 are swung inwardly over the finished side of the strip toward each other, covering that portion 95 of the finished side of the strip which intervenes the folds. The fastening devices 26 are inserted through the portion 20 of the welt, securing the same in place against the article and the beaded folds 16 are held 100 downwardly over the fastening devices by virtue of the tension exerted in the welt when the marginal portions are spread outwardly and the welt fastened in place, as 105 shown in Fig. 2.

In Fig. 2 I have shown the welt as used to cover the edge of a trim sheet 24 applied to a body member 22, fastening devices 26 being inserted to hold the same in place.

5 These fastening devices exert a tension on the welt which maintains the beaded folds 16 in their covering relationship.

What I claim is:

- 10 1. A finishing welt formed of a strip of flexible material, each longitudinal marginal portion of which is folded over and fastened down along the fold thus formed, said marginal portions extending beyond their points of fastening to cover one side 15 of the intervening portion of the strip and adapted to be spread apart to swing the folds toward each other over the opposite side of such intervening portion of the strip.
- 20 2. A finishing welt formed of a strip of flexible material having a finished side and an unfinished side, each longitudinal marginal portion of the strip folded over on the unfinished side and stitched down along the fold thus formed, said longitudinal 25 marginal portions extending over the strip beyond the stitching and adapted to be spread apart to swing the folds toward each other over the finished side of the strip to cover that portion thereof which intervenes 30 in the folds.
- 35 3. A finishing welt formed of a strip of flexible material having a finished side and an unfinished side, each longitudinal marginal portion of the strip folded over a filler cord on the unfinished side of the strip and

stitched alongside the cord thereby forming a beaded fold, said marginal portions extending toward each other beyond the stitching over the unfinished side of the strip and adapted to be spread apart whereby the beaded folds are swung together over the finished side of the strip.

4. A finishing welt formed of a strip of flexible material having a finished side and an unfinished side, each longitudinal marginal portion of the strip folded over on the unfinished side over a filler cord and stitched down along such cord thereby forming beaded folds, said marginal portions of the strip extending over the unfinished side to meet 50 between the beaded folds.

5. The combination with an article of a finishing welt applied thereto formed of a strip of flexible material having a finished side and an unfinished side, each longitudinal portion of which strip is folded over upon the unfinished side and stitched down along the beaded fold thus formed, said strip being applied to the article by securing means extending through that portion 60 which intervenes the beaded folds with the unfinished side of the strip placed against the article and the marginal folds spread apart bringing their unfinished sides against the article and swinging the folds together 65 over the securing means.

In testimony whereof, I sign this specification.

EARLE A. EMERY.
